UNITED STATES PATENT OFFICE.

GEORGE F. HUTCHINS, OF WORCESTER, MASSACHUSETTS.

DESIGN FOR A JACK-LEVER.

SPECIFICATION forming part of Design No. 28,579, dated May 10, 1898.

Application filed December 23, 1897. Serial No. 663,268. Term of patent 14 years.

To all whom it may concern:

Be it known that I, GEORGE F. HUTCHINS, a citizen of the United States, residing at Worcester, in the county of Worcester and State of Massachusetts, have invented and produced a new and original Design for Jack-Levers for Shedding Mechanisms, of which the following is a specification, reference being had to the accompanying drawings, forming a part thereof.

My invention relates to a jack-lever or harness-jack for loom shedding mechanism; and my invention consists in a new and original design for a jack-lever, as will be more fully described hereinafter.

In the accompanying drawings, Figure 1 is a side elevation of a jack-lever embodying my design. Fig. 2 is a section of the same, taken through one of the arms.

The leading feature of my design for a jack-lever consists of curved end portions and a series of notches on the inner edge of each curved end portion, the inner ends of which lie in a curved line or arc of a circle drawn through the inner ends of the two end notches of each series.

In Fig. 1 is shown a jack-lever embodying my design, having a horizontal arm 1, curved at its end portion, a series of notches 3 on its

inner edge, the inner ends of which lie in a curved line or arc of a circle α , drawn through the inner ends of the two end notches, so that the inner end of each notch 3 will be the same distance from the axis or center of the circle of which the line α is an arc, and consequently the notches 3 intermediate the two end notches will not be in the same straight line with said end notches, as shown by the line b .

The vertical arm 2 is curved at its end portion and has a series of notches 4 upon its inner edge, the inner ends of which lie in a curved line or arc of a circle X X , drawn through the inner ends of the two end notches, so that the inner end of each notch 4 will be the same distance from the axis or center of the circle of which the line X X is an arc. Consequently the notches 4 will not be in the same straight line with said end notches, as shown by line Y Y .

Having thus described my invention, I claim—

The design for a jack-lever, substantially as shown and described.

GEO. F. HUTCHINS.
